UNITED STATES PATENT OFFICE

SEBASTIAN L. CALVERT, OF COWETA, OKLAHOMA, ASSIGNOR OF ONE-HALF TO
CHARLES F. LEECH, OF BARTLESVILLE, OKLAHOMA.

PUMP.

1,160,840.

Specification of Letters Patent. Patented Nov. 16, 1915.

Original application filed July 1, 1913, Serial No. 776,843. Divided and this application filed July 17, 1914.
Serial No. 851,551.

To all whom it may concern:

Be it known that I, SEBASTIAN L. CALVERT, a citizen of the United States, residing at Coweta, in the county of Wagoner and State 5 of Oklahoma, have invented new and useful Improvements in Pumps, of which the following is a specification.

This invention is an improved oil pump for pumping oil from oil wells and consists 10 in the construction, combination and arrangement of devices hereinafter described and claimed.

One object of the invention is to provide an improved pump of this character which 15 includes means for separating the sand and earthy particles from the oil while pumping the oil and causing the sand to be precipitated.

Another object is to effect improvements 20 in the construction of the plunger.

This application is a division of my co-pending application for Letters-Patent of the United States for improvements in pumps, filed July 1, 1913, Serial No. 776,843, 25 allowed Feb. 24, 1914.

In the accompanying drawings:—Figure 1 is a vertical sectional view of the operating parts of an oil well pump constructed in accordance with my invention. Fig. 2 is a detail elevation, on a larger scale, of the plunger. Fig. 3 is a detail vertical sectional view of the same. Fig. 4 is a detail sectional view of the upper portion of the pump, showing the plunger tube valve and 35 also showing the check valve in which the plunger tube operates. Fig. 5 is a similar view of the lower portion of the pump, showing the lower or standing valve and its connections. Fig. 6 is a sectional view of 40 the same on a plane indicated by the line *a—a* of Fig. 1.

In accordance with my invention, I provide an outer tubular body 1, which forms a casing for the sand chamber 2, the upper 45 end of the said tubular body being connected by a suitable reducer 3 to the lower end of the pump tube 4 which reaches to the top of the well and the lower end of the said outer tubular body 1 is screwed to the outer 50 side of the upper portion of a reducer 5, the lower end of the reducer being connected by a sleeve 6 to the upper end of a perforated inlet tube 7, which is arranged in the bot-

tom of the well and in which oil enters by the rock pressure.

In the upper portion of the reducer 5 is a 55 threaded opening 8 in which is screwed the lower end of a tubular cage 9, the upper portion of which is closed as at 10 and provided with openings 11 in its wall, the said 60 cage being formed with a valve seat 12 and a ball valve 13 being employed which is arranged in the upper portion of the cage and is adapted to close downwardly on the seat.

In the casing or outer barrel 1 is an inner 65 or working barrel 14 which is of less diameter than the outer barrel, is spaced therefrom and the lower end of which is screwed to the upper end of the reducer as at 15. The upper end of the working barrel is provided with a conical seat 16 having a removable packing head 17 and to the upper end of the working body is screwed the reduced upper end 18 of a tubular or annular shield or apron 19 the diameter of which 70 exceeds that of the working barrel so that the said shield or apron is arranged around and spaced from the upper portion of the working barrel and in and spaced from the outer barrel 1. The lower end of the said 75 shield or apron is open. The working barrel is provided near its upper end, at a point within the shield or apron with openings 20. The plunger 21 which is arranged to operate in the working barrel has a threaded 80 central opening and is screwed to the lower end of a tube 22. Two pairs of split packing rings which are preferably made of brass and are indicated at 23—24 are arranged at some distance apart on the plunger 85 tube, the lower member of the lower packing rings 23 bearing directly on the plunger. A nut 25 is screwed on the plunger tube 22 and bears against the upper side of the upper ring 24 and between the rings 90 23—24 are a series of valve cups 26 which are made of leather or other suitable material and are separated from each other by washers 27 which are also arranged on the plunger tube 22 and are adapted to fit in 100 the depressed central portions of the valve cups. The length of the plunger tube is such that its upper end extends above the working barrel. The plunger tube is free 105 to move vertically through a central opening in the removable packing head 17 and

the upper end of the plunger tube, which is somewhat reduced, is screwed to the lower end of a cage 28 in which is a ball valve 29 which is adapted to close downwardly on 5 the seat 30 with which the cage is provided. The wall of the cage has openings 31 and the cage is closed at its upper end as at 32 and provided with a threaded stem 33 to which is screwed the lower end of a plunger 10 rod 34 which extends to the upper end of the well and is employed to impart vertical reciprocating motion to the plunger and its plunger tube.

The removable packing head 17 is provided on its upper side with rings 35 which fit snugly around the plunger tube and while permitting the plunger tube to reciprocate prevents sand from going through the said removable packing head.

20 In the operation of my improved oil pump, oil is sucked into the lower portion of the working barrel, at each upstroke of the plunger with its tube 22 and valve 29, the valve 13 opening and the valve 29 closing. On each down stroke of the plunger, 25 the valve 29 opens and the valve 13 closes and oil is forced upwardly through the plunger tube 22 and past the valve 29 into the upwardly extending tube 4.

30 The barrel or outer body 1 fills with oil as the result of the operations of the plunger and is kept full during the operation of the pump and such sand or other like material as is in the oil becomes precipitated and 35 settles in the sand chamber 2 which is formed by the space between the barrel or outer body 1 and the working barrel 14. The openings 20 in the upper portion of the working barrel prevent air from being compressed therein and interfering with the 40 operation of the plunger and the shield or apron 19 which is arranged around the upper end of the working barrel covers the

said openings and prevents sand or the like from entering the working barrel, above the 45 plunger through the said opening. The removable packing head 17 forms in effect a stuffing box for the plunger tube and prevents sand from entering the upper portion 50 of the working barrel.

The arrangement and construction of the parts of my improved oil pump are such as to greatly facilitate the assembling and disassembling of the same and, hence, enable all parts of the pump to be readily inspected 55 and repaired, and also enable the sand which accumulates in the said chamber to be discharged therefrom periodically as needed.

While I have herein shown and described 60 a preferred form of my invention, I would have it understood that changes may be made in the form, proportion and construction of the several parts without departing from the spirit of the invention and within 65 the scope of the appended claim.

Having thus described my invention, I claim:—

An oil pump plunger comprising a tubular body having a diametrically reduced intermediate portion and having its upper and lower end portions each provided with a peripheral annular groove, packing rings fitted in the said grooves and cups on the reduced intermediate portion and between 70 75 said portions, the said packing rings being adapted to fit closely in a pump barrel and prevent sand or the like from getting to the cups.

In testimony whereof I affix my signature 80 in presence of two witnesses.

SEBASTIAN L. CALVERT.
